UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Original application filed March 28, 1921, Serial No. 456,396. Divided and this application filed March 17, 1922. Serial No. 544,494.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to a rail anchor or anti-creeper, and a primary object of the invention is to provide a novel device of this type which will be light, strong, compact, economical to manufacture and so constructed as to have a great holding power as against the tendency of the rail to creep.

15 A further object is to provide a rail anchor of novel construction which can be used on rails of different sizes and having rail bases of different configuration.

20 A further object is to provide a rail anchor which, in addition to the characteristics referred to above, will take a positive hold on the rail, that is to say, is not dependent upon the creeping stress of the rail to hold the anchor in its rail gripping position so that, if the device is provided with an abutment, it will hold the rail against longitudinal movement in either direction.

25 A further object is to so construct the rail anchor that it may be removed and replaced repeatedly without impairing its holding power.

The invention consists of the new and improved constructions, arrangements and devices to be hereinafter described and claimed for carrying out the above stated objects and such other incidental objects as will be referred to in the accompanying description.

30 The invention is illustrated, in a preferred embodiment in the accompanying drawing wherein

Fig. 1 is a plan view of a railroad rail showing a rail anchor constructed in accordance with my invention applied thereto.

35 Fig. 2 is a sectional view taken on line 2—2 of Fig. 1.

Fig. 3 is a fragmentary view in perspective, of the yoke member of the anchor, and

40 Fig. 4 is a view in perspective of the key member employed in connection with the yoke member.

Like characters of reference designate like parts in the several figures of the drawing.

Referring to the drawing, 10 designates a railroad rail and 11 one of the cross ties supporting the rail. The rail anchor is preferably of the two piece type, consisting of a rail base embracing yoke member 12 and a key 13 adapted to be driven between the yoke member and the bottom surface of the rail base. The yoke member 12 is made, preferably, of a relatively high carbon steel so as to be resilient. It may be formed by cutting and bending a piece or blank of sheet metal. The yoke member consists of a bar 14 to extend under the base 15 of rail 10, a foot or tie abutting flange 16 and hooks or jaw forming portions 17 and 18 made by bending over the ends of the bar 14. The lip 70 of jaw 18 is longer than that of jaw 17. The jaws are formed with openings 19 and 20 for the key 13 which, as shown in Figs. 1 and 2, is driven through openings 19 and 20, between the bottom of the rail base 15 and the bar 14 of the yoke member. The openings 19 and 20 are preferably arranged in staggered relation with each other so that the key 13 stands obliquely to the rail. The purpose of this is to check the tendency of 80 the yoke to rock on the key and to provide a convenient arrangement whereby the key may be driven home without encountering the difficulties which would otherwise be presented if the large end of the key 13 were 85 in closer proximity to the tie 11.

The jaws 17 and 18 are preferably formed so that they are bent when the key 13 is driven home. The dotted lines in Fig. 2 indicate, approximately, the original contours of the jaw, the full lines showing the strained contour thereof when the yoke is under the wedging pressure of the key.

90 The key 13 is preferably wedge shaped and is bowed in the direction of its length 95 so that it will be distorted when it is driven home between the rail base and the bar 14 of the yoke. The key is preferably made of relatively high carbon steel so that when it is in its applied position it will function as 100 a spring to resist any tendency that the vibration of the rail may have to move it in

the direction from which it was driven or otherwise loosen its wedging position between the rail base and the anchor.

It will be seen that the holding power of a rail anchor constructed as above described will be very great in proportion to its size and weight. The device has a resilient engagement with the rail so that its hold thereon is not easily affected by vibration or other disturbing influences. The key has a very gradual taper and is stressed when in its applied position, therefore, having but little tendency to back out of the position to which it is driven. The lips of jaws 17, 18 are strained when the wedge is driven home. The device is easily applied to a rail by first hooking the jaw 18 over the rail base, raising the yoke and moving it in the direction of its length (to the left of Fig. 2) until jaw 17 is engaged with the other edge of the rail base, then driving the key 13 into position between the under surface of the rail base and the yoke member. The device is as easily removed from the rail by driving the key from its small end. The anchor may be used repeatedly without detrimentally affecting its holding power. The same anchor may be used on rails of different sizes and somewhat different cross sectional configurations. For rails beyond the limits of adjustment of any given key the device may be adapted without change in the yoke by merely using a wider or narrower key. The yoke stands at some distance below the bottom of the rail base, particularly at the right hand end (Fig. 2) so that the tie abutting flange 16 does not have to be very long in order to obtain a firm bearing on the tie even when the latter is of the hewn type. Assuming an abutment for the flange 16 on both sides thereof, for example, when the abutment is embedded in the ballast of the roadbed, the anchor will prevent the rail creeping in either direction.

This application is a division of my co-pending application Serial No. 456,396, filed March 28th, 1921.

I claim:

1. A rail anchor comprising a rail base 50 engaging member having a resilient jaw portion and a curved resilient key adapted to be driven crosswise of the rail between the under face of the rail base and a subjacent portion of the yoke.

2. A rail anchor comprising a rail base 65 embracing yoke, and a wedge-shaped key bowed to provide resiliency and adapted to be driven between the under face of the rail base crosswise of the rail and a subjacent portion of the yoke.

3. A rail anchor comprising a rail base 80 embracing yoke, and a curved resilient key adapted to be driven between the under surface of the rail base crosswise and diag-

nally of the rail and a subjacent portion of the yoke.

4. A rail anchor comprising a rail base 60 embracing yoke having an opening therein, and a bowed spring metal key adapted to be driven through the opening between the 70 under surface of the rail and a subjacent portion of the yoke.

5. A rail anchor comprising a rail base 75 embracing yoke having an opening therein, and a wedge-shaped key bowed to provide 75 resiliency and adapted to be driven through the opening between the under face of the rail base and a subjacent portion of the yoke.

6. A rail anchor comprising a spring 80 metal rail base embracing yoke, and a curved spring metal key adapted to be driven between said base and yoke to effect a rail gripping strain in the latter.

7. A rail anchor comprising a spring 85 metal rail base embracing yoke and a curved spring metal key adapted to be distorted by driving the same between said base and yoke to effect a rail gripping strain in said key and yoke.

8. A rail anchor comprising a spring 90 metal rail base engaging yoke and a key bowed in the direction of its length adapted to be driven between said base and yoke crosswise of the rail to effect a rail gripping strain in the yoke.

9. A rail anchor comprising a spring 95 metal rail base engaging yoke formed with an opening, and a curved resilient key adapted to be driven through said opening between the rail base and yoke to effect a 100 rail-gripping strain in the latter.

10. A rail anchor comprising a spring 105 metal rail base engaging yoke formed with an opening, and a wedge shaped key adapted to be driven through said opening between the rail base and yoke to effect a rail gripping strain in the latter; said key being curved in the direction of its length and stressed when in its applied position.

11. A rail anchor comprising a rail base 110 engaging member having a spring lip to extend over the top of the rail base, and a spring metal key bowed in the direction of its length adapted to be driven between said rail base and a subjacent portion of said engaging member, to produce a binding strain in said lip.

12. A rail anchor comprising a yoke member 115 having spring lips to engage opposite upper faces of the rail base, and a wedge-shaped, spring metal key bowed vertically adapted to be driven between said rail base and a subjacent portion of said yoke, to produce a binding strain in said lips.

13. A rail anchor comprising a rail base 120 embracing yoke having resilient hook portions to overlap opposite edges of the rail base, and a bowed, wedge-shaped, spring

metal key adapted to be driven between said rail and a subjacent portion of the yoke, to produce a binding strain in said hook portions of said yoke.

- 5 14. A rail anchor comprising a rail base embracing yoke having resilient hook portions to overlap opposite edges of the rail base, and a bowed, wedge-shaped, spring metal key adapted to be driven between said rail and a subjacent portion of the yoke, to produce a binding strain in said key and said hook portions of said yoke.

15. A rail anchor comprising a spring metal yoke member bent at opposite ends to

provide lips to overlap opposite edges of the rail base, and a bowed key adapted to be driven crosswise of the rail between said rail base and a subjacent portion of the yoke to produce binding strains in said lips.

16. A rail anchor comprising a spring 20 metal yoke member bent at opposite ends to provide lips to overlap opposite edges of the rail base, and a bowed key adapted to be driven crosswise and diagonally of the rail between said rail base and a subjacent 25 portion of the yoke to produce binding strains in said lips.

ROLANDIS A. BLAIR.
